US00D360407S

United States Patent [19]

Collas et al.

[11] Patent Number: Des. 360,407

[45] Date of Patent: ** Jul. 18, 1995

[54] COMPUTER WITH BUILT IN JOYSTICK AND CLICK BUTTONS

[75] Inventors: **James P. Collas**, N. Sioux City, S. Dak.; **Michael R. Flannery**, Sioux City, Iowa

[73] Assignee: **Gateway 2000**, North Sioux City, S. Dak.

[**] Term: **14 Years**

[21] Appl. No.: **20,166**

[22] Filed: **Mar. 16, 1994**

[52] U.S. Cl. **D14/100**; D14/114

[57] CLAIM

The ornamental design for a computer with build in joystick and click buttons, as shown and described.

DESCRIPTION

FIG. 1 is a reduced perspective view of the computer with built in joystick and click buttons according to the invention;

FIG. 2 is a top plan view thereof;

FIG. 3 is an end elevation thereof; and,

FIG. 4 is a side elevation thereof.

The side elevation from the opposite side of FIG. 4 would be a mirror image of FIG. 4.

The broken lines shown unclaimed environmental structure and are intended to show the nature and intended application of the claimed design.

FIG. 1

FIG. 2

FIG. 3

FIG. 4
